UNITED STATES PATENT OFFICE.

FRANK A. HUNTINGTON, OF SAN FRANCISCO, CALIFORNIA.

ROCK CRUSHER OR BREAKER.

SPECIFICATION forming part of Letters Patent No. 324,937, dated August 25, 1885.

Application filed July 14, 1884. (No model.)

To all whom it may concern:

Be it known that I, FRANK A. HUNTINGTON, of the city of San Francisco, in the county of San Francisco and State of California, have 5 invented an Improvement in Rock Crushers or Breakers; and I hereby declare the following to be a full, clear, and exact description thereof.

My invention relates to an apparatus for 10 breaking or crushing rock or other similar material.

It consists in the combination of devices 15 hereinafter described and claimed.

Referring to the accompanying drawings for 20 a more complete explanation of my invention, Figure 1 is a side elevation of my improved rock-crusher. Fig. 2 is a vertical section taken in a plane longitudinally through the axes of the shaft.

25 A is a fixed jaw, which may be of any material sufficiently strong to resist the operation of crushing, and which is supported upon a suitable frame-work, B. The upper end of this jaw may be supported in any suitable 30 manner. In the present case I have shown it as supported upon a strong transverse shaft or bolt, C, and the lower end rests upon a square bar, D. It may be raised so as to approach the opposite crushing-face as fast as it becomes 35 worn by the introduction of plates E between the upper side of this bar and the back of the die A. The actual crushing-face of this die consists of a shoe, F, the inner surface of which is curved to a radius greater than that of the 40 opposing cylindrical crushing-face, and its back is of the same curve as the die A, against which it fits. The upper part of this shoe, which is bolted to the die A, has a projecting lug, G, which extends across its face for a

45 H is a cylinder, which is mounted upon a shaft, I, upon which it turns loosely. That part of the shaft which passes through the cylinder H is made eccentric to the portion 50 which turns in the journal-boxes, and it turns loosely within the cylinder, so that when the shaft is rotated its action is to move the cylinder in a small circle. The shaft I is journaled in a horizontal plane, preferably below 55 the middle of the shoe F of the stationary crushing-jaw, so that the space between the upper part of this stationary shoe and the cyl-

inder is considerably greater than the space between its lower portion and the cylinder, as shown.

55 J is a bushing or sleeve fitted within the cylinder H, so that the shaft I turns within it, and this bushing has considerable length, so as to have a long bearing-surface on the shaft and prevent rapid wear. Whatever wear does 60 occur will take place on this bushing, which is keyed within the cylinder. Whenever the bushing is worn out it can be easily replaced with another. Lubrication between this bushing and the eccentric shaft may be effected 65 through a hole bored longitudinally into the shaft, and having small holes, L, extending from it to the space between the shaft and bushing. This hole may be filled with any suitable lubricator and the outer end plugged 70 up, when it will run for a considerable length of time without further attention.

75 M are small oil-holes, also made through the hub of the cylinder, through which the oil may be introduced for the same purpose, if desired. Upon the exterior of this cylinder H is secured a ring, die, or shoe, N, which may be made of wrought-iron, steel, cast-steel, or other suitable tough material which will 80 resist the action of the rock between itself and the fixed die F. This ring die may either be shrunk upon the cylinder or made loose and the space filled with lead or other material, or it may be made in sections and bolted on.

85 O represents a hopper, through which the rock or material to be crushed is fed into the space between the fixed die F and the die N on the rotary cylinder.

90 The shaft I is caused to rotate by means of a belt upon the pulley P, or by any suitable means for driving the shaft. The operation will then be as follows: The cylinder H is carried around in a small circle by the rotation of the eccentric shaft I, and alternately approaches to and recedes from the fixed die 95 F, so that any rock which falls between the two will be broken in the upper part, fall a little lower and be again broken, and so on, being reduced at each descent until it reaches the narrowest space between the two, where 100 it can pass out. The lug or projection G, at the upper side of the shoe F, is important, because it prevents rock from being forced outward when the cylinder approaches the

shoe, the rock being held beneath this projection until it can be acted on and crushed by the movement of the cylinder. It will be seen that if the rotation of the shaft I is upward on 5 the side toward the fixed shoe that the cylinder will approach the lower part of the die F first and the upper part afterward; but if the rotation be in the opposite direction, or downward on the side toward the fixed die, the upper part of the cylinder will approach this die first and the lower part afterward. As the cylinder or its interior bushing turns loosely upon the shaft, it will be seen that the action of the cylinder will simply be to approach and recede from the fixed jaw without partaking 10 of the revolving movement of the shaft. There will, however, be a slight forward movement of the cylinder in the direction of the rotation of the shaft at each forward and backward movement with relation to the die, so 15 that the cylinder always presents a new face to act against the rock between the two, and will gradually complete the revolution. The

plates E, which fit over the bar D, upon which the lower end of the jaw A rests, serve to move 25 it toward the cylinder as fast as the shoe F becomes worn, so that the space at the lower end will not become too wide, and this adjustment may be made until it is necessary to replace the shoe with another.

Having thus described my invention, what I claim as new, and desire to secure by Letters Patent, is—

A crushing apparatus comprising a frame provided with a hopper, an eccentric shaft, a loose cylinder upon said shaft, a fixed jaw formed with a projection, G, the bolt C, bar D, and plates E, substantially as and for the purpose specified.

In witness whereof I have hereunto set my hand.

FRANK A. HUNTINGTON.
